BUCKLE

Josef Hora, deceased, late of Melide, Switzerland,
by Walther Trautwein, administrator, Burg,
Germany, assignor to Gerber & Co., Melide,
Switzerland

Application November 7, 1950, Serial No. 194,472
In Switzerland November 8, 1949

1 Claim. (Cl. 24—170)

1

This invention relates to a buckle for securing together two straps or belts or two portions of the same strap or belt, such as the two ends of a garment belt, whereby one of the said straps or belts is retained in the buckle by squeezing engagement.

One object of the invention is to provide a buckle capable of reliably retaining, by such squeezing engagement, straps or belts of different thicknesses without requiring mechanical adjustment of the buckle.

A further object of the invention is to provide a buckle which can be easily manufactured in particular from synthetic resin.

Other objects and advantages of the invention will appear from the following description of an embodiment thereof, by way of example, with reference to the accompanying drawing in which:

Fig. 1 is a longitudinal section of a belt buckle, and

Fig. 2 is a plan view of the same.

In the drawing, the reference number 1 indicates a closed, rectangular frame comprising longitudinal portions or elements 13 and transverse portions or elements 14, 15 as well as a bridge 2 extending between the longitudinal elements 13 and parallel to the transverse elements 14, 15. All these elements and the bridge 2 are preferably manufactured integral with each other, for instance from synthetic resin. The bridge 2 serves for permanently attaching to the buckle one end 3 of a garment belt by plying it around the said bridge to form a loop and closing the latter by sewing or riveting the overlapping parts of the belt together. Parallel to the bridge, two short pivot lugs 4 facing each other are formed on the inner face of the longitudinal frame elements. Moreover two flat lugs 12 are provided on the inner face of these elements so as to form abutment faces substantially in the central plane of the frame.

Pivots mounted in the frame 1 there is an H-shaped movable squeezing member consisting of a first transverse portion or pivot leg 6 both ends of which are provided with recesses 5 for engagement with the lugs 4, a second transverse portion or pressure leg 7 parallel to the pivot leg 6, and a central longitudinal portion or bridge connecting the two legs at their middle. The pressure leg 7 has a longitudinal slot 9 and carries a number of lugs 10, which in the described example are three in number and which face the transverse portion 15 of the frame 1 so as to leave only a small gap 16 therebetween. Swinging of the described movable squeezing member around

2

the axis of the pivot lugs 4 is limited to one side of the frame 1 by the ends of the pressure leg 7 abutting against the abutment faces of the above-mentioned lugs 12 of the frame 1. The movable member preferably is also an integral piece made from a suitable synthetic resin. Both its legs 6 and 7 and its bridge 8 are each of such cross-section as to permit elastic flexion. In particular, the slot 9 in the leg 7 makes its front portion carrying the lugs 10 very resilient.

To secure the other end 11 of the belt or girdle 3, the movable squeezing member 6, 7, 8 is swung upwards to increase the gap 16 between the lugs 10 and the adjacent transverse element 15 of the frame 1. Then, the end 11 of the belt is drawn through this gap from beneath, and the movable squeezing member again pressed down until its leg 7 abuts against the lugs 12 of the frame. Due to the presence of the belt 11 in the gap 16 the lugs 10 are thereby forced back, and the leg 7, as well as the bridge 8 and the pivot leg 6 of the movable member are resiliently flexed, all as shown in dot-and-dash lines in Fig. 2, so that the lugs 10 exert a pressure on the belt, thus squeezing the latter between the lugs 10 and the transverse member 15 of the frame and securing it in position. The extremity of the belt end 11 finally can be drawn through the interval between the opposite transverse element 14 of the frame and the bridge 2, in order to cover the movable member and give the belt closure a neat appearance, as well as to prevent opening of the buckle by accidental traction on that belt extremity.

If the resilience of the movable member is conveniently chosen, belts in a large range of different thicknesses upwards from the minimum width of the gap 16 can be firmly secured with buckles of the described construction, without having to resort to different buckle sizes or mechanical adjustment means for the movable squeezing member.

What is claimed is:

A buckle comprising a closed frame member made from synthetic resin and having longitudinal and transverse portions, and a squeezing member made from resilient synthetic resin having two resilient transverse portions connected to each other at their centers by a longitudinal portion, the ends of one of the said transverse portions of the said squeezing member and the opposed internal faces of two longitudinal portions of the said frame member being provided, on one member, with integral short pivot lugs, and on the other member, with complementary recesses for receiving said lugs, whereby the said

squeezing member is swingable in said frame member to and from a position in which the other transverse portion of the said squeezing member faces a transverse portion of said frame member with a narrow gap therebetween for resiliently squeezing a belt or strap in said gap, the said other transverse portion of the said squeezing member having at least one transverse slot to increase its flexibility.

WALTHER TRAUTWEIN,
*Administrator of the Estate of Josef Hora,
 Deceased.*
